CRIMPING TOOL

John R. Vickery, York, Pa., assignor to Aircraft-
Marine Products Inc., Harrisburg, Pa.

Application February 17, 1950, Serial No. 144,657

4 Claims. (Cl. 140—113)

1

This invention relates to a heavy duty hydraulic power tool and more particularly to an electrically controlled hydraulically powered heavy duty crimping tool assembly supported to permit substantially complete universal movement translationally and rotatably for manual movement into a variety of working positions and locations.

This invention may be advantageously used in the manufacture of large capacity electrical apparatus and the like. In such manufacture it is frequently necessary to apply, for example, heavy duty electrical connections by crimping to heavy cables in inaccessible locations. It is desirable if such heavy connectors can be crimped by more or less portable crimping machinery, yet the force necessary satisfactorily to crimp or apply such heavy connectors may require crimping apparatus of such great bulk or weight that it is difficult manually to bring the crimping apparatus into position for satisfactory use.

In accordance with the present invention hydraulically powered heavy duty apparatus may be constructed to deliver adequately forceful crimping pressure for the application of heavy electrical connectors and the like and yet such heavy duty apparatus may be supported or suspended in constant tension fashion for ready manual movement into a variety of working positions and locations with substantially complete universal translational and rotatable and swinging movement.

It is a principal object of this invention to provide a heavy duty hydraulic power tool of the character described adapted for ready manual movement into a variety of working positions and locations.

A further object of this invention is to provide constant tension support means for a heavy duty power tool of the character described adapted for substantially complete universal translational rotating and swinging movement.

A still further object of this invention is to provide suspension or support means for a heavy duty power tool of the character described whereby substantially all of the weight of the tool may be pivotally and rotatably carried by said support means to permit relatively easy manual positioning of the tool notwithstanding the bulk or weight thereof.

Still another object of this invention is to provide an electrically controlled heavy duty hydraulically powered crimping tool for the application of large electrical connectors and the like.

2

Still a further object of this invention is to provide a heavy duty hydraulically powered crimping tool of the character described, the crimping jaws of which are of reduced dimensions to admit of insertion and use into spaces of limited accessibility.

Other objects and advantages of this invention will be apparent from the following description, the accompanying drawings, and the appended claims.

In the application of heavy electrical connectors to large cables, bus bars and the like in the manufacture of heavy duty transformers, etc., it is desirable to provide means for fastening such connectors to such heavy cables by crimping them around the cable. Frequently this crimping operation can most advantageously be done in relatively inaccessible portions of, for example, a large transformer, and it is accordingly desirable that such connections be crimped by means of portable crimping apparatus. However, the force necessary satisfactorily to accomplish this crimping operation is of such great magnitude that it may most advantageously be applied by very heavy-duty equipment.

The weight of such crimping or pinching apparatus required for such uses and the bulk of such apparatus may be sufficiently great as to curtail or preclude manual portability and manipulation of the apparatus. Rigidly supported or permanently placed heavy duty crimping apparatus, however, does not answer the problem since such crimping operations frequently require the crimping apparatus to be moved about to successive locations of the connections in the electrical apparatus to which crimped connectors are to be applied.

Accordingly it is desirable that the crimping apparatus be readily adapted for portability and substantially complete universal movement in all directions and in all positions and yet so suspended or supported that the operator of the apparatus is relieved of the necessity of supporting the heavy weight of the crimping apparatus.

Reference is now made to the drawings which illustrate preferred embodiments of this invention and in which like parts are designated by the same numerals.

Figure 1 is a perspective view in side elevation showing the entire electrically controlled hydraulically powered crimping tool supported in counter-balanced fashion;

Figure 2 is a view in elevation from the operating end of the tool of Figure 1 shown supported upon a movable stand;

Figure 3 is a vertical section of the mounted crimping assembly taken along the line 3—3 of Figure 2;

Figure 4 is a front view of the tool of Figure 2 shown to an enlarged scale to illustrate means according to the present invention for providing rotational movement of the crimping assembly;

Figure 5 is a top plan view of the sub assembly of Figure 4; and

Figure 6 is a diagrammatic view of the controls for the supply of the pressure fluid to the tool.

As shown in Figure 1 apparatus embodying this invention consists generally of hydraulically operated, pressure applying crimping jaws 10 pivotally mounted on a carriage 11 which is freely rotatable within a circular race or ring 12. The circular race 12 may be suspended by a flexible connection from counter-balancing means indicated conventionally in the drawing as a cable 13 passing over pulleys 14 to counter-balancing weights 15, or by an arm stand on casters, etc. Suitable hydraulic fluid is supplied under pressure to the crimping assembly by a pump assembly indicated diagrammatically at 16 and flexibly connected with the crimping assembly by suitable flexible fluid supply line 17. Handles 18 are mounted on the crimping assembly for manual swinging movement of the jaws 10 with respect to the carriage 11 or for manual rotational movement of carriage 11 within race 12 or for transitional movement of the entire crimping assembly and its mounting by virtue of the flexible support means 13. The operation of the tool is controlled by remote control means, described in detail hereinafter, mounted on the crimping assembly and connected to the pumping assembly by suitable wires, not shown.

The crimping assembly includes a pair of levers which provide coacting jaws 10 pivoted together at 25 for movement to and away from each other. The outer ends 26 of the jaws 10 project beyond i. e., forwardly from the ring 12 and are reduced in width as shown for ready insertion into spaces of limited size. The forward ends 26 of the jaws 10 carry crimping dies 27 adapted for the desired crimping of an electrical connector or other object placed therebetween. The dies 27 may conveniently be pivotally mounted between the ends 26 of the jaws 10 so that they may be rotated within the jaws 10 to receive, for instance, an electrical cable which may be either perpendicular to the jaws 10 or aligned therewith.

Between the opposite or rearwardly ends 30 of the jaws 10 and connected therewith is an hydraulic cylinder-and-piston motor comprising cylinder 31 and piston 32 arranged so that the introduction of hydraulic fluid into the cylinder 31 through inlet 33 will cause the piston 32 to move in a direction to force the ends 30 of jaws 10 away from each other and, consequently, causing the forward ends 26 of the jaws 10 to be forced into closing relation. Counteracting the force of the hydraulic piston 32 and spring means 34 which bias the forward ends 26 of the jaws 10 toward open position by forcing the rearward ends 30 of the jaws 10 and the piston 32 toward each other when the pressure of hydraulic fluid on piston 32 is released.

The crimping assembly, including the jaws 10 and the cylinder and piston motor 31, 32, is pivotally mounted upon the carriage 11 for swinging movement with respect thereto. Carriage 11 may have a T shape as shown in the drawing, being composed of perpendicular structural members each with a roller at its end. The crimping assembly is mounted on the carriage by means of

the leg or post 40 thereof passing through the parallel longitudinally extending slots 42, Figure 3, in the forward end portions of bifurcated frame pieces 41. These frame pieces 41 which are connected at their rearward ends to form in effect a rocking bracket also carry pivot 25 of the jaws 10 so that the crimping assembly may be mounted substantially at its center of gravity on carriage 11 yet the pivot 25 along the center line of the jaws 10 will remain stationary with respect to the handles 18 during crimping or clamping movement of the jaws relative to each other. Frame pieces 41 also carry suitable handles 18 for manipulation of the crimping assembly and its mounting.

The T-shaped carriage 11 carries at its three extreme points rollers 50, which in this case are standard ball bearing assemblies to provide free rotation of the carriage 11 within the circular groove or race 51 in the outer ring 12.

Hydraulic fluid may conveniently be supplied to the cylinder 31 for work against the piston 32 by a suitable pumping assembly 16 through flexible supply line 17 and connections 17' and 17'' to inlet 33 in cylinder 31. Such pumping assembly 16 is shown diagrammatically in Figure 6. The pumping assembly may include a suitable pump 60, driven by any suitable means such as a motor 61, and a reservoir 62 from which hydraulic fluid is pumped and to which it is returned upon release of the pressure within cylinder 31. As indicated diagrammatically in Figure 6, a pressure relief valve 63 is positioned adjacent the outlet 64 of the pump 60 to by-pass further pumping of hydraulic fluid after a predetermined hydraulic pressure has been achieved. The setting of valve 63 may be adjusted so that a maximum pressure may be established and automatically maintained between the jaws 10 of the crimping assembly.

Positioned in the fluid supply line 17—17' between the valve 63 and the inlet 33 to cylinder 31 is an electrically controlled, two position, three way valve 70 shown in diagrammatic cross-section in Figure 6. Valve 70 operates vertically in the diagram shown and includes a plunger 71 operating within valve walls 72. In the uppermost position of plunger 71, inlet 73 from the pump 60 is connected by passage 74 in the plunger 71 to the valve outlet 75 so that hydraulic fluid is supplied from the pump 60, under the control of by-pass valve 63, through inlet 73, passage 74 and outlet 75 to the supply line 17 and thence to cylinder 31. In the lowermost position (not shown) of plunger 71 inlet 73 from pump 60 is effectively cut off by plunger 71 and the supply line 17 is connected by passage 74 (through outlet 75) to return line 77 leading from valve 70 back to the reservoir 62. Consequently when the plunger 71 of valve 70 is in its upper position, fluid will be supplied by the pump 60 to cylinder 31, but when the plunger 71 of valve 70 is in its lower position, further supply of fluid from pump 60 to cylinder 31 will be cut off and the fluid in cylinder 31 will be forced out of the cylinder by the action of spring means 34 tending to pull together the ends 30 of jaws 10 and will return through supply line 17 to the reservoir 62. Also, when the plunger 71 of valve 70 is in its lower position, the pump 60 may be stopped and, in any event, its output would be by-passed by pressure relief valve 63 as soon as the maximum pressure is attained against the closed valve 70.

In the case illustrated, the movement of the plunger 71 of the valve 70 is controlled by the solenoid 84 or other motor means directly or through a known type of linkage. Spring means 83 is

provided to press the plunger 71 back in a direction opposite to that in which it is urged by action of the motor 84. As shown, the valve is open from the crimper to the reservoir when the solenoid is released and is open from the pump to the crimper when the solenoid is actuated.

The solenoid as shown is controlled by any of several switches. One of these is in each of the handles 18 operated by the triggers 66 in the respective handles. Another switch 67, advantageously a microswitch mounted on the side of the crimper where it is engaged by an arm attached to the other jaw of the crimper, is actuated to cut off both the motor 61 and the solenoid 84 precisely at the end of the required 15 crimping operation. Instead of the microswitch 67 on the crimper, or in addition to it, there may also be a switch actuated by pressure in the line 17 so that when the desired maximum crimping pressure is achieved, the current to the motor 61 and the solenoid 84 are thus cut off.

In place of the counter-balanced suspension shown in Figure 1, the crimping assembly and its mounting may be supported as in Figure 2 on a movable stand composed of telescoping members 80 and 81 adapted for adjusting the height of the stand and a suitable base 82 which may be provided with suitable casters 83 for ready movement into position for operation of the tool.

While the forms of apparatus herein described 30 constitute preferred embodiments of the invention, it is to be understood that the invention is not limited to these precise forms of apparatus, and that changes may be made therein without departing from the scope of the invention which 35 is defined in the appended claims.

What is claimed is:

1. A portable tool for applying solderless connectors comprising in combination a supporting ring, a frame mounted to rotate freely within said ring, said frame including a post disposed in diametrical relation across the opening of said ring, a U-shaped bracket extending through the opening of said ring and having parallel arms each provided with a longitudinally extending slot having an open forward end, said bracket being supported on and in rocking relation to said post with the rearward closed ends of said slots embracing said post, a pair of levers extending through the opening of said ring and pivotally mounted on 45 said bracket between said arms at the forward

open end portions of said slots, said levers having co-operating die-carrying jaws at their forward ends, spring means normally biasing said jaws toward open position, and a cylinder and fluid actuated piston motor operatively interposed between and supported between rearward end portions of said levers, said cylinder being connected to said post and rotatable thereon coaxially with said bracket.

2. Portable tool according to claim 1 and wherein said spring means includes spring supporting yokes, one engaging a grooved rearward end portion of each of said levers, and tension springs connecting the ends of said yokes.

3. Portable tool according to claim 1 and wherein the cylinder has a lug projecting laterally from an intermediate portion of its wall, and a hole extending transversely through said lug receives said post.

4. Portable tool according to claim 1 and wherein said bracket supports laterally extending handles having means for controlling jaw closing movement of said piston while an operator holds the jaws in work engaging position.
